US00D782825S

(12) **United States Design Patent** (10) **Patent No.:** **US D782,825 S**
(45) **Date of Patent:** **** Apr. 4, 2017**

(54) **TOOTHBRUSH**

(71) Applicant: **COLGATE-PALMOLIVE COMPANY**, New York, NY (US)

(72) Inventors: **Douglas J. Hohlbein**, Hopewell, NJ (US); **Al Sprosta**, Maplewood, NJ (US); **Alan Sorrentino**, Cranbury, NJ (US)

(73) Assignee: **COLGATE-PALMOLIVE COMPANY**, New York, NY (US)

(**) Term: **15 Years**

(21) Appl. No.: **29/529,021**

(22) Filed: **Jun. 3, 2015**

Related U.S. Application Data

(62) Division of application No. 29/481,114, filed on Jan. 31, 2014, now Pat. No. Des. 732,831, which is a (Continued)

Primary Examiner — Susan Moon Lee

(57) **CLAIM**

We claim the ornamental design for a toothbrush, as shown and described.

DESCRIPTION

FIG. 1 is a perspective view of a toothbrush according to the present invention.

FIG. 2 is a front view of the toothbrush of FIG. 1.

FIG. 3 is a rear view of the toothbrush of FIG. 1.

FIG. 4 is a left-side view of the toothbrush of FIG. 1.

FIG. 5 is a right-side view of the toothbrush of FIG. 1.

FIG. 6 is an angled front view of the toothbrush of FIG. 1.

FIG. 7 is a top view of the toothbrush of FIG. 1; and,

FIG. 8 is a bottom view of the toothbrush of FIG. 1.

The broken line portions within the above listed drawings are illustrative of the environmental structure or boundaries of the contemplated design and form no part of the claimed design.

1 Claim, 4 Drawing Sheets

Related U.S. Application Data

division of application No. 29/418,938, filed on Feb. 24, 2012, now Pat. No. Des. 700,437, which is a division of application No. 29/331,929, filed on Feb. 5, 2009, now Pat. No. Des. 660,599.
